UNITED STATES PATENT OFFICE.

GEORGE W. WARNER, OF FREEPORT, ILLINOIS.

DOOR-HANGER.

SPECIFICATION forming part of Letters Patent No. 429,295, dated June 3, 1890.

Application filed December 14, 1889. Serial No. 333,722. (No model.)

To all whom it may concern:

Be it known that I, GEORGE W. WARNER, of Freeport, in the county of Stephenson and State of Illinois, have invented certain new and useful Improvements in Door-Hangers; and I do hereby declare that the following is a full, clear, and exact description thereof, reference being had to the accompanying drawings, and to the letters of reference marked thereon, which form a part of this specification.

This invention relates to that class of improvements known as "door-hangers," employed for supporting doors from the top, and wherein the axles of the wheels or rollers of the hanger run on horizontal rails located above the door, and the hanger is secured to the top of the door.

The main and primary object of the invention is to embody in a door-hanger of simple and durable construction mechanism by which the several parts thereof may be perfectly and accurately adjusted with respect to each other and to the door, so that the latter will hang perfectly true. This I accomplish by the arrangement of the connecting-links, as will hereinafter more fully appear.

Another object of the invention is to provide automatic and perfect locking devices, whereby the main portion of the hanger and that portion thereof secured to the door will be securely locked together by the simple act of placing the two parts in operative positions.

The invention consists in the novel construction and combination of devices herein illustrated and described, and more particularly pointed out in the appended claims.

In the drawings, Figure 1 shows a side elevation of the door-hanger embodying my invention applied to the upper portion of a door, the rail for supporting the roller being partially broken away. Fig. 2 illustrates the same in an end elevation. Fig. 3 illustrates in vertical sectional view the plate secured to the top of the door and that portion of the hanger adapted to engage said plate. Fig. 4, in two parts, shows in perspective view the automatic locking mechanism for securing together the hanger and the door-plate.

In the drawings, A is the door. B B are suitable rails, preferably of wood, although

sometimes of iron, secured at a suitable distance above the door, and upon which the wheels or rollers C C run.

55

A' is a metal plate of the width of the door A, adapted to be secured thereto by means of screws a or other suitable means. The said plate A' is provided with a central longitudinal recess a', the adjacent walls of which recess taper toward each other, thus making the recess dovetailed in shape, as clearly shown in Figs. 3 and 4. As a matter of fact, the plate A' is constructed of two bars joined together by transverse bars or webs a² at suitable intervals, as clearly shown in dotted lines in Fig. 1, and it is through these web portions that the screws a are passed.

60

C' is a rider-bar, preferably of cast metal, having a straight bearing-edge c adapted to rest upon the axle c' of the wheels or rollers C C. The forward end of the rider-bar C', which is bent downwardly and rearwardly, terminates in an enlargement or bearing C², having a horizontal elongated transverse slot 65 or opening c². The rear end of the rider-bar C' is provided with a downwardly-extending arm C³, at the lower end of which is an enlargement c³. In said arm above this enlargement c³ is an inclined transverse opening or 70 slot c⁴.

75

D is a plate provided with a dovetailed extension or rib d upon its lower face, which dovetailed extension d is adapted to be inserted in the dovetailed recess a' of the plate A', whereby the said plates D and A' may be united. The plate D is provided at its forward end with a raised lug d' and near its rear end with a second lug d², the latter having an elongated transverse slot d³ therein. 80 The plate D is also provided at its rear end with a third lug d⁴. This lug d⁴ is an enlarged extension of the plate D, and is provided with an upwardly-extending slot or opening d⁵.

85

E is an adjusting-screw adapted to be passed from the under side of the lug d⁴ through the hole or opening d⁵ therein and then into the opening in the enlargement c³ of the depending arm C³. The head e of the adjusting-screw E rests upon the under side of the lug d⁴ and the end of the said screw engages the nut c⁵, located in the lower end of the slot c⁴ of the arm C³. It is obvious that by turning 90

95

100

this adjusting-screw E to the right or left the rider-bar C' may be raised or lowered accordingly.

F is a link movably connected at one end 5 to the lug d' of the plate D and at its other end to the depending arm C³ of the rider-bar C' by means of pivot-pins f f'.

F' is a second link, movably secured at its ends in the slots c² and d³ of the arm C² and 10 of the lug d², respectively, by the pivot-pins f' f'', which latter are adapted to travel in said slots, as will be readily understood. The links F and F', which cross each other as 15 shown, are secured together by the pivot-pins f''.

It will thus be understood that a very free movement of the links F and F' on their respective pins f f' f'' is made possible by the 20 location of the pins f' f'' in the slots c² d³, and also that a greater range of adjustment is possible by the construction employed. Any strain on the several parts is equalized, 25 and greater strength is imparted to the whole structure by this novel arrangement of the links F and F'.

As a separate and further improvement, I 30 provide a link D', preferably of wire, and hinge or pivot the same to the plate D in any convenient manner. The end d⁶ of the link D' extends at right angles to the main portion of the link and is adapted to engage the forward shoulders or faces of the upwardly-extending lugs a³ of the plate A. These lugs a³ are formed by cutting away a portion of 35 the sides of the plate A', as clearly shown in Fig. 4, thus forming also a pair of shoulders a⁴, opposite the lug a³. a⁵ is a lug or stop located upon the upper face of the forward end 40 of the plate A', and against which the end of the plate D may rest, if desired.

The operation of my invention is as follows: The plate A' is first secured to the upper edge of the door A by means of the screw a, so that the shoulders or lugs a³ will come 45 adjacent to the end of the door. The hanger is then placed in position with the wheels C resting upon the tracks B. The forward end of the plate D is then brought into juxtaposition to the rear end (that end bearing 50 the shoulders a³) of the plate A'. The plate D is secured to the plate A' by having its dovetailed flange d passed into the dovetailed recess or opening a' of the plate A', the movement of the plate D with respect to 55 the plate A being indicated by the arrow in Fig. 1. The plate D is moved in the direction indicated a sufficient distance—that is, until the transverse arm d⁶ of the link D' has passed over the lugs a³. It will be obvious 60 that the weight of the link D' will cause the arm d⁶ thereof to seek the lowest point of the cut-away portion of the plate A', and that any movement of the plate D in the direction opposite to that shown by the arrow in 65 Fig. 1 will be arrested by reason of the engagement of said arm d⁶ with the said lugs a³. The forward movement of the plate D

with respect to the plate A' will be similarly arrested by reason of the engagement of the link D' with the shoulders a⁴.

It is manifest from the above description that the plates D and A' will be locked together automatically by the simple act of sliding the one in and upon the other. To remove the plate D from the plate A' it will 75 be simply necessary to raise the arm d⁶ of the link D' vertically a sufficient distance to clear the top of the shoulders or lugs a³, whereupon the plate D may be moved bodily backward, as will be manifest.

The vertical adjustment of the rider-bar C' with respect to the bar D may be accomplished, as above stated, by the adjusting-screw E. It will be understood that when, by 85 movement of the screw E, the rider-bar C' is raised said rider-bar C' will remain in a position parallel to that of the plate D during said adjustment by reason of the slotted pivotal connection of the link F' with said rider-bar and with the plate D. I am thus enabled 90 to obtain an accuracy and nicety of adjustment by the simple turning of the screw E, preserving at all times the parallelism of the rider-bar C' and the plate D.

It will be understood of course that the location of the slots c² d³ may be varied without producing any appreciable effect upon the operation of the links, provided one slot is on the rider-bar and the other is in the plate D. For example, the slot d³ might be 100 located in the lug d', if desired. I regard this construction and arrangement of the links and their connections as very important and as constituting the main feature of my invention.

What I claim is—

1. In a door-hanger, the combination of a rider-bar, a base-plate, and two connecting-links, said links being movably connected to each other and to said rider-bar and base-plate, and means for adjusting the position of the base-plate with respect to the rider-bar, substantially as specified.

2. In a door-hanger, the combination of a rider-bar provided with a slot or elongated 115 opening, with a base-plate provided with an elongated slot, a link movably connected to said rider-bar and base-plate in the slots therein, a second link pivoted to said first-mentioned link and to the base-plate and 120 rider-bar, and an adjusting-screw in engagement with said base-plate and rider-bar, substantially as described.

3. In a door-hanger having a two-part base-plate, the two parts being united by sliding 125 the one over the other, a pivoted gravity pawl or link secured to the upper half and adapted to engage suitable shoulders or lugs on the lower half of said base-plate, whereby said two parts are automatically locked together.

4. In a door-hanger, the combination of the plate A', provided with lugs a³ a⁵ and a recess a', of the part D, secured to the hanger

by suitable links, said part D having a depending rib d , adapted for engagement with the recess a' , and a gravity-arm D' , adapted to engage the shoulder or lugs a^3 , whereby 5 said plates A' and D are substantially locked together when placed in operative position.

In testimony that I claim the foregoing as

my invention I affix my signature in presence of two witnesses.

GEORGE W. WARNER.
